H. M. KNIGHT

HIGHWAY CONSTRUCTION

Filed Oct. 27, 1919

INVENTOR
Herbert M. Knight

UNITED STATES PATENT OFFICE.

HERBERT M. KNIGHT, OF MONTCLAIR, NEW JERSEY.

HIGHWAY CONSTRUCTION.

Application filed October 27, 1919. Serial No. 333,562.

To all whom it may concern:

Be it known that I, HERBERT M. KNIGHT, a citizen of the United States, and resident of Montclair, in the county of Essex and 5 State of New Jersey, have invented certain new and useful Improvements in Highway Constructions, of which the following is a specification.

My invention relates to improvements in 10 highways constructed in part or in whole of precast units.

One of the objects of my invention is to provide parallel tracks or runways for 15 treads of wheels of vehicles at definite distances apart. Another object is to unite the cross ties connecting the parallel runways together by articulated keys, so as to permit a latitude of adjustment in installing. Still another object is to provide an inde- 20 structible wearing surface under the treads of vehicles of limited width, giving a limited opening between said tracks of inde- structible wearing surface, to be constructed of cheaper and less resistant mate- 25 rials. A further object of the invention is to provide a roadway of parallel tracks with a resilient strip of wearing surface upon said tracks. Another object of the 30 said invention is to reduce the cost of pav- ements by limiting the amount of costly non- abrasive wearing surface to that portion of 35 the roadway on which vehicles usually travel, and constructing the balance of the pavement of a less resistant material. A further object of the invention is to provide 40 such a type of roadway as that some portion, not greater than one half thereof, can be constructed and put into operation while the other portion is in service or while that portion of the original pavement or road- way, is being used for traffic.

The accompanying drawings Nos. 1-15 are 45 illustrative of the invention.

Figure 1 is a plan view of a completed 50 roadway having runways so disposed as that two vehicles can pass at all stages thereof.

Figure 2 is a section of plan view of such 55 a roadway without the resilient wearing surface upon the tracks and without the cheaper superficial material between the tracks.

Figure 3 is a plan view of a double

tracked roadway without the superficial and resilient surfaces, with openings therein showing the cross ties in position before 55 the introduction of the parallel tracks.

Figure 4 is a plan view showing the tracks and cross ties in position with the re- 60 sili ent wearing material upon the tracks and without the cheaper inter-track mate- rial in place.

Figure 5 is a cross section of such a road- 65 way on line 5—5 of Fig. 1.

Figure 6 is a cross section of a side track and joint as at 6—6 of Fig. 2 and Fig. 7. 65

Figure 7 is a longitudinal section through a side track at a joint on line 7—7 of Fig. 6.

Figure 8 is a plan view of such a joint with a portion of the resilient wearing sur- 70 face removed to show certain features of the joint.

Figure 9 is a cross section of a center track for a two track roadway, as at point 9—9 of Fig. 2.

Figure 10 is a cross section of the uniting 75 key holding and connecting the various units together.

Figure 11 is a cross section of a single 80 track roadway as at 11—11 of Fig. 12.

Figure 12 is a plan view of a completed 85 single track highway.

Figure 13 is a sectional plan view of a single track highway without the resilient 90 wearing surface in the tracks.

Figure 14 is a sectional plan view of a single track roadway with openings left to 95 show the ties in position without the tracks and key in said ties.

Figure 15 is a plan view of single track 100 highway with the resilient material in the tracks, but without the inter-track surfacing material.

While the material of which these tracks and ties will probably be constructed is concrete, it is distinctly understood that this 105 invention does not limit itself to the use of this material either wholly or partly in the construction thereof, but is intended to cover its application to any form of highway construction and material to which it is 110 applicable.

Referring to the drawings, in which simi- 115 lar figures refer to similar parts, 1 is a side track composed of a precast material, such

as concrete; 2 are precast central tracks composed of similar material; 3 are ties of precast material, having reentrant grooves; 4 is a groove in the upper surface at pre-determined points; 5 is a re-entrant groove of the side and central tracks and adapted to register with the re-entrant groove 4 of the ties; 6 is a key adapted to enter the aligned re-entrant grooves 4 and 5 and 10 unite the sides and tracks together; 7 is a joint on the side tracks; 8 is a joint on the center tracks; 9 are re-entrant grooves in the two center tracks which register together; 10 is a key adapted to enter the 15 aligned registering re-entrant grooves 9 and unite the center tracks together longitudinally; 11 are dowel holes in the ends of contiguous tracks; 12 are dowels inserted in said dowel holes; 13 is a trough or depression in the top of said side and center tracks 1 and 2; 14 undercut walls for retaining within said trough 13 a wearing strip, 15 placed in said trough; 16 a superficially treated surface between the side tracks or between 20 the side and center tracks; 17 a superficially treated surface on the shoulders exterior to the side tracks; 18 is an upward projection from the side of the side tracks to form a curb or other retaining structure along the 25 said side tracks; 19 is an asphaltic, cementitious, or bituminous filling around said key 6 and within said re-entrant grooves 4 and 5; 20 pouring holes in said side and central tracks for the purpose of pouring said 30 cementitious material into the space between the said units and around and within the said keys and reentrant grooves; 21 locating ridges on ties for the purpose of locating them accurately in position, so that the re-entrant grooves of the tracks and ties will 35 properly register; 22 is the line of the original surface of the ground before the introduction of this improved pavement; 23, bottom cross ribs, are introduced to prevent 40 crawling of the track on heavy grades.

In the construction of highways for automobile and motor traffic, a new and less abrasive type of pavement than that formerly sufficient for horse drawn vehicles, 50 has become a necessity. Resistant pavement is expensive in first cost, thereby limiting the amount of pavement which can be laid, especially in the rural districts on account of the high cost of installation. 55 Traffic over most highways, develops along certain definite lines. If confined to these lines by reason of a superior traffic way or wearing surface, it becomes unnecessary to cover the entire width of the roadbed of the 60 highway with a continuous sheet of resistant material but this resistant material can be confined to certain narrow, longitudinal strips along which travel will proceed. The place between said strips if filled with a less 65 resistant material will reduce the cost of

the roadway without in any way interfering with its value and giving equally good traffic conditions to those existing where the road over which the entire width of the travel way has been covered with the more expensive resistant material. 70

In the operation of constructing a road of the type herein described, if built for the passage of a single vehicle and without provision for a continuous stream of traffic in 75 both directions, two longitudinal tracks or ways are provided, united together by a tie of precast material. In building this roadway, absolute adherence to the original surface of the roadway is not required but excavation is made across the width of the existing roadway only to such depth as is necessary for the introduction of the ties. Before these are accurately spaced, the longitudinal tracks are laid upon the ties, keys having been introduced into the re-entrant grooves along the under side of the tracks previous to placing in the roadway, but without fastening into the track. The keys are slidably movable along the track until they enter the re-entrant groove upon the upper surface of the tie, after which both ties and tracks are aligned by means of the locating ridges 21 and tamped to grade. 80 After the ties and tracks are in place, a cementitious or bituminous material is poured through pouring holes 20 so as to surround the keys and fill the re-entrant grooves thereby binding the track and ties together. The balance of the roadway between the tracks is then filled with ordinary earth or other suitable material to a point just below the crown of the finished roadway when any type of road material, such as broken stone and water or oil bound 85 macadam, can be introduced completing and crowning the roadway between the two tracks and extending outwardly, if designed, to form the shoulders 17 of any desired 90 width. 100

In the construction of a two track roadway where provision is made for continuous passage in both directions of vehicles, the operation is similar to that herein mentioned for a single track road, except that the ties 3 are provided on one end with multiple re-entrant grooves 4 for the purpose of uniting with the multiple central track. The operations in this case are similar to those in a single track roadway, except that excavation for ties and the placing of the tracks proceeds for only one half of the roadway at a time, thereby leaving the other half in its original condition so that traffic 115 may continue thereon uninterruptedly, or so that after the introduction of half of the roadway, traffic may be diverted to the completed half while the construction of the remaining half is under way. 120

It is evident from Fig. 5 and Fig. 11 that 130

by the process herein set forth, it is possible to construct a new highway without excavating below the ground surface or of the original highway, except for so much as may be required for the placing of the ties. Material excavated for this purpose being placed over said ties and around said tracks upon which subsequently is placed a superficial and comparatively inexpensive inter-track and shoulder road material. This obviates the necessity of removing from the site of the work, the excavated material as is often the case with present road constructional methods and allows for the utilization of most, if not all, of the material as filling in making the new roadway, and also materially reduces the amount of excavation required.

It is seen that at joint locations resting upon ties, the joints are lapped and in order to preserve the alinement of said joints, dowel holes are left, into which dowels are introduced thereby preventing the crawling of the track and maintaining it in proper longitudinal and transverse alignment. On heavy grades, despite this method of construction, difficulties might ensue in the crawling of the track, if the entire construction at the joint were not such as to make ties and track work together and for this purpose ribs 23 transverse to the track are constructed so as to engage the side of the ties 3 in case of crawling and cause the ties and tracks to work in unison.

It is expected that the tracks of this roadbed would be constructed of concrete, either reinforced or not, and, necessarily whatever material of construction was used in the making of the tracks, the joints thereof would be exposed unless covered up by some material, such exposure resulting in disintegration from frost and wearing from traffic. Again in certain climates, a more resilient material than concrete might be desired on which the treads of the vehicle might travel. For this purpose, the tracks are made with depressions, having undercut walls and a wearing strip of material other than the track material, such as asphalt, brick or some combination of bituminous binder with a broken stone or gravel basis is introduced therein, such strip covering the joints in the tracks thereby protecting them and at the same time, making a continuous unjointed strip on which the treads of said vehicles may travel.

What I claim is:—

1. The combination of tracks and ties having grooves in their juxtaposed surfaces.
2. The combination of tracks and ties having registering grooves in their juxtaposed surfaces.
3. The combination of precast tracks and precast ties having registering grooves in their juxtaposed surfaces.

4. The combination of tracks and ties, having re-entrant registering grooves in their juxtaposed surfaces.

5. The combination of precast tracks and precast ties having re-entrant registering 70 grooves in their juxtaposed surfaces.

6. The combination of tracks and ties having grooves in their juxtaposed surfaces, and keys connecting said tracks and ties.

7. The combination of pre-cast tracks and 75 pre-cast ties having grooves in their juxtaposed surfaces and keys connecting said pre-cast tracks and pre-cast ties.

8. The combination of tracks and ties having registering grooves in their juxtaposed 80 surfaces, and keys connecting said tracks and ties.

9. The combination of pre-cast tracks and pre-cast ties having registering grooves in 85 their juxtaposed surfaces, and keys connecting said tracks and ties.

10. A roadbed composed of tracks resting on ties which have grooves in their upper surface.

11. A roadway composed of tracks having 90 grooves on their under surface, resting upon ties having grooves in their upper surface, the said grooves in said tracks and ties registering in alignment.

12. A roadway composed of tracks connected by ties attached to said tracks by means of keys inserted in registering 95 grooves in said tracks and ties.

13. A roadway composed of precast tracks resting on precast ties having grooves in 100 their upper surfaces.

14. A roadway composed of precast tracks having grooves on their under surface resting upon precast ties, having 105 grooves in their upper surface, the said grooves in the said tracks and ties registering in alignment.

15. A roadway composed of precast tracks connected by precast ties and attached to said tracks by keys inserted in 110 registering grooves in said tracks and ties.

16. A center track for a roadway consisting of parallel juxtaposed tracks, having grooves in their adjacent surfaces.

17. A center track for a roadway consisting of parallel juxtaposed tracks having 115 registering grooves in their adjacent surfaces.

18. A center track for a roadway consisting of parallel juxtaposed tracks having 120 registering undercut grooves in their adjacent surfaces.

19. A center track for a roadway consisting of parallel juxtaposed tracks connected together by a key.

20. A center track for a roadway consisting of parallel juxtaposed tracks having 125 registering grooves in their adjacent surfaces and a key inserted therein connecting the two tracks.

21. A center track for a roadway consisting of parallel juxtaposed tracks having registering undercut grooves in their adjacent surfaces and a key inserted therein connecting the two tracks. 65
22. A center track for a roadway consisting of parallel juxtaposed tracks, the parts connected together by a key. 70
23. The combination of a center track made up of a multiple of parallel parts 10 connected by keys. 75
24. The combination of a center track made up of a multiple of parallel precast parts connected by keys. 80
25. A centre track for a roadway connected to cross ties by keys. 85
26. A centre track for a roadway, composed of a multiple of parallel tracks, said tracks being connected to cross ties by keys. 90
27. The combination of a centre track composed of a multiple of parallel tracks, undercut grooves in the under surfaces of the tracks, cross ties with undercut grooves in their upper surfaces and keys connecting said tracks and ties. 95
28. The combination of a centre track having undercut grooves on the under surface thereof, side tracks having undercut grooves on the under surfaces thereof, said 100 tracks resting on ties having undercut grooves on the upper surfaces thereof, and keys connecting said tracks and ties. 105
29. The combination of a centre track, composed of a multiple of parallel tracks, having undercut grooves on the under surfaces thereof, side tracks having undercut grooves on the under surfaces thereof, said 110 tracks resting on ties having undercut grooves on the upper surfaces thereof, and keys connecting said tracks and ties. 115
30. Ties for a roadway connected by a key to a side track and also connected by keys to all parts of a center track. 120
31. In a roadway, ties connected to side and centre tracks said ties overlapping in the middle of said roadway. 125
32. In a roadway, ties connected to side and centre tracks by keys, said ties overlapping in the centre of said roadway. 130
33. In a roadway, the combination of ties and tracks, said ties being connected to all parts of a centre track and to one side track. 135
34. In a roadway, the combination of pre-cast ties and pre-cast tracks, said ties being connected to all parts of a centre track, and to one side track. 140
35. In a roadway the combination of ties and tracks connected by keys, said ties being connected to all parts of a centre track and to one side track. 145
36. In a roadway, ties, undercut grooves in the upper surface of said ties, tracks supported upon the said ties, undercut grooves 150
- in the under surface of said tracks, said grooves in said ties and in said tracks registering, keys in said registering grooves and alinement means on the upper surface of said ties. 155
37. In a roadway, ties, undercut grooves in the upper surface of said ties, tracks supported upon said ties, undercut grooves in the under surface of said tracks, said grooves in said ties and in said tracks registering, keys in said registering grooves and alinement means on the upper surface of said ties and integral therewith. 160
38. In a roadway, pre-cast ties, undercut grooves in the upper surface of said ties, pre-cast tracks supported upon the said ties, undercut grooves in the under surface of said tracks, said grooves in said ties and in said tracks registering, keys in said registering grooves and alinement means on the upper surface of said ties. 165
39. In a roadway, pre-cast ties, undercut grooves in the upper surface of said ties, pre-cast tracks supported upon the said ties, undercut grooves in the under surface of said tracks, said grooves in said ties and in said tracks registering, keys in said registering grooves and alinement means on the upper surface of said ties and integral therewith. 170
40. In a roadway, side tracks resting upon ties, a central track composed of a multiple of parallel tracks resting upon ties, undercut grooves in the upper surface of said ties, undercut grooves in the under surface of said tracks, said grooves in said ties and in said tracks registering, keys in said registering grooves, said ties being discontinuous across said roadway. 175
41. In a roadway, side tracks resting upon ties, a central track composed of a multiple of parallel tracks resting upon ties, undercut grooves in the upper surface of said ties, undercut grooves in the under surface of said tracks, said grooves in said ties and in said tracks registering, keys in said registering grooves, said ties alternately connecting opposite side tracks with said central track. 180
42. In a roadway, side tracks resting upon ties, a central track composed of a multiple of parallel tracks resting upon ties, undercut grooves in the upper surface of said ties, undercut grooves in the under surface of said tracks, said grooves in said ties and in said tracks registering, keys in said registering grooves, said ties being discontinuous across said roadway, alternately connecting opposite side tracks with said central track and overlapping transversely beneath said central track. 185
43. In a roadway, tracks supported upon ties, undercut grooves in the under surface of said tracks, undercut grooves in the upper 190

surface of said ties, said grooves in said tracks and in said ties registering, keys in said grooves, said ties being increased in thickness beneath the said tracks.

5 44. In a roadway, pre-cast tracks supported upon pre-cast ties, undercut grooves in the under surface of said tracks, undercut grooves in the upper surface of said ties, said grooves in said tracks and in said 10 ties registering, keys in said grooves, said ties being increased in thickness beneath the said tracks.

15 45. In a roadway, a tie having a single undercut groove at one end and a multiple of undercut grooves at the other end, and keys, connecting said ties with a side track and with the multiple parts of a centre track.

20 46. In a roadway, a pre-cast tie having a single undercut groove at one end and a multiple of undercut grooves at the other end, and keys, connecting said ties with a pre-cast track at one end and a multiple of keys, connecting said ties with the multiple parts of a pre-cast centre track at the other end.

25 47. In a roadway, the combination of tracks connected to ties by keys, said tracks having troughs in their upper surfaces.

30 48. In a roadway, the combination of pre-cast tracks connected to pre-cast ties by keys, said tracks having troughs in their upper surfaces.

35 49. In a roadway, the combination of tracks connected to ties by keys, said tracks having troughs in their upper surfaces with undercut walls.

40 50. In a roadway, the combination of pre-cast tracks connected to pre-cast ties by keys, said tracks having troughs with undercut walls in their upper surfaces.

45 51. In a roadway, the combination of tracks connected to ties by keys, said tracks having troughs in their upper surfaces, said troughs being filled with resistant wearing material.

50 52. In a roadway, the combination of pre-cast tracks connected to pre-cast ties by keys, said tracks having troughs in their upper surfaces, said troughs being filled with resistant wearing material.

55 53. In a roadway, the combination of tracks connected to ties by keys, said tracks having troughs with undercut walls in their

upper surfaces, said troughs being filled with resistant wearing material.

54. In a roadway, the combination of pre-cast tracks connected to pre-cast ties by keys, said tracks having troughs with undercut walls in their upper surfaces, said troughs being filled with a resistant wearing material. 60

55. In a roadway, the combination of tracks connected to ties by keys, and a material of lesser wearing resistance forming the surface of the roadway between said tracks. 65

56. In a roadway, the combination of pre-cast tracks connected to pre-cast ties by keys, and a material of lesser wearing resistance forming the surface of the roadway between said tracks. 70

57. In a roadway, the combination of tracks connected to ties by keys, troughs in the upper surfaces of said tracks, said troughs being filled with a resistant wearing material and a material of lesser wearing resistance forming the roadway between said tracks. 75

58. In a roadway, the combination of pre-cast tracks connected to pre-cast ties by keys, troughs in the upper surfaces of said tracks filled with a resistant wearing material and a material of lesser wearing resistance forming the roadway between said tracks. 80

59. In a roadway having pre-cast tracks resting upon pre-cast ties and connected to said ties by keys inserted in grooves in said tracks and ties, means for grouting said keys after insertion in said grooves. 85

60. In a roadway having pre-cast tracks resting upon pre-cast ties, and connected to said ties by keys, holes in said tracks for grouting said keys after insertion in grooves in said tracks and ties. 90

61. A roadway composed of precast tracks resting upon precast ties and connected to said ties by means of keys with a less resistant superficial material between said tracks. 100

62. A combination of precast tracks connected by keys to precast ties with a less resistant superficial material between said tracks. 105

Signed at New York city, in the county of New York and State of New York, this 24th day of October A. D., 1919.

HERBERT M. KNIGHT.
